(57) **CLAIM**

The ornamental design for a dovetail anchor assembly, as shown and described.

DESCRIPTION

FIG. 1 is a top left perspective view of a dovetail anchor assembly in accordance with the present invention; FIG. 2 is a top right perspective view thereof; FIG. 3 is a bottom left perspective view thereof; FIG. 4 is a bottom right perspective view thereof; FIG. 5 is a front view thereof; FIG. 6 is a back view thereof; FIG. 7 is a right side view thereof; FIG. 8 is a left side view thereof; FIG. 9 is a top side view thereof; and, FIG. 10 is a bottom side view thereof.

The broken lines that are immediately adjacent to claimed surfaces are considered to be boundary-type broken lines. All other broken lines which show features within broken line boundaries show portions of the dovetail anchor assembly that form no part of the claimed design.
